[57] CLAIM

The ornamental design for a golf club putter head, substantially as shown.

DESCRIPTION

FIG. 1 is a perspective view of a golf club putter head showing my new design, as seen from the right front quarter,

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and

FIG. 7 is a right side elevational view thereof.

FIG. 6
